DESIGN FOR A FLUORESCENT LIGHTING FIXTURE

Leonard F. Hirsh, Philadelphia, Pa.

Application March 23, 1940, Serial No. 91,190

Term of patent 7 years

To all whom it may concern:

Be it known that I, Leonard F. Hirsh, a citizen of the United States and residing at Philadelphia, in the county of Philadelphia and State of Pennsylvania, have invented a new, original, and ornamental Design for a Fluorescent Lighting Fixture, of which the following is a specification, reference being had to the accompanying drawing, forming part thereof, and in which:

Fig. 1 is a perspective view of the fluorescent lighting fixture showing my new design, and
Fig. 2 is a transverse section upon the line 2—2 of Fig. 1.

I claim:

The ornamental design for a fluorescent lighting fixture, substantially as shown.

LEONARD F. HIRSH.
